UNITED STATES PATENT OFFICE.

CURTIS HUSSEY VEEDER, OF HARTFORD, CONNECTICUT.

DESIGN FOR A CYCLOMETER-CASE.

SPECIFICATION forming part of Design No. 26,945, dated April 20, 1897.

Application filed January 18, 1897. Serial No. 619,689. Term of patent 14 years.

To all whom it may concern:

Be it known that I, CURTIS HUSSEY VEEDER, a citizen of the United States, residing in the city and county of Hartford, State of Connecticut, have invented a certain new and original Design for Cyclometer - Cases, of which the following is a specification, reference being had to the accompanying drawings, forming a part hereof.

10 My invention relates to a design for cyclometer cases or shells for supporting the operative parts of such and similar instruments; and it consists in a cyclometer-case having the shape and configuration substantially as shown in the accompanying drawings, in which—

Figure 1 is a perspective view of a shell or case which embodies my design. Fig. 2 is a side elevation of the shell or case shown in Fig. 1, and Fig. 3 is an end elevation thereof.

Referring particularly to the drawings, it will be seen that the body *a* of the shell or

case is substantially cylindrical, while lengthwise of one side, substantially parallel with the axis of the cylinder, is arranged a rib or 25 protuberance *b*. In the side of the body is an opening *c*, and in one end thereof is an aperture *d*.

The leading feature of my design, however, is the substantially cylindrical body with a 30 protuberance or rib arranged lengthwise of the body and substantially parallel with the axis thereof.

What I claim, and desire to secure by Letters Patent, is—

35 The design for a cyclometer-case substantially as shown and described.

This specification signed and witnessed this 14th day of January, A. D. 1897.

CURTIS HUSSEY VEEDER.

In presence of—

H. L. BOCK,
E. BARRIE SMITH.
